[57] CLAIM

The ornamental design for a combined rear view mirror and wiper unit, as shown and described.

DESCRIPTION

FIG. 1 is a perspective view of the top, front and one side of a combined rear view mirror and wiper unit showing my new design;

FIG. 2 is a front elevational view thereof;

FIG. 3 is a rear elevational view thereof;

FIG. 4 is a side elevational view thereof, the side opposite being a mirror image of the side shown in FIG. 4;

FIG. 5 is a top plan view thereof; and,

FIG. 6 is a bottom plan view thereof.

FIG. 1

FIG. 2

FIG. 3

FIG. 4

FIG. 5

FIG. 6
